(57) **CLAIM**

The ornamental design for a wooden furniture surface ornamentation, as shown and described.

DESCRIPTION

The single view is illustrative of a surface ornamentation according to the present invention as applied to a bed. The ornamentation is characterized in that the several section patterns are made distinctive from another by use of woods having different grain appearances. While the ornamentation is applied to a bed, it should be realized that it could be used on doors, drawers, and the like.

The broken lines are for environmental purposes only and form no part of the claimed design.
